UNITED STATES PATENT OFFICE.

BURT A. CHUBBUCK, OF McDONALD, PENNSYLVANIA.

MACHINE FOR DIGGING TUNNELS.

Application filed March 12, 1921. Serial No. 451,861.

This invention relates to machines for cutting tunnels, digging coal, removing the vertical surface from ledges of rock, etc. The object of the invention is to improve the mechanism of machines adapted to the purposes above referred to, and operating by means of a plurality of reciprocating cutting blades driven by compressed air, steam, or other fluid pressure. Additional purposes and advantages of the invention will be apparent to those familiar with the art from the following specification.

Referring to the drawings, Fig. 1 is a diagrammatic side elevation and partial vertical section showing the mounting of the cutting mechanism; Fig. 2 is a plan view of a part of the machine, comprising a pair of tool-driving cylinders, partly in horizontal section; Fig. 3 is a partial plan and diagram showing a modification; Fig. 4 is a section on line 4—4 of Fig. 3; and Fig. 5 is a partial elevation in enlarged form showing one of the pressure regulating valves and its operative connections.

In cutting tunnels, entry ways in coal veins, and the like, it has long been desired to have a machine which will remove the surface of the material through which the cut is being made over the entire end of the opening that is to be made. In order to do this without blasting, it is necessary to remove the material in comparatively small pieces, that is to say, by chipping it off with hammer like blows as opposed to under-cutting and knocking down in large masses. For this purpose, various machines have been devised, having a plurality of cutting blades or tools which are driven against the surface of material to be cut, the blades being moved from place to place, so as not to dig holes in the material, but, on the contrary to chip it off in comparatively small portions. It is to this class of machines that the present invention relates, and specifically it relates to such machines driven by fluid pressure.

The invention is particularly concerned with the means for supplying, controlling and regulating the pressure of the fluid driving means to secure uniform and certain action of the mechanism, and to cushion the stroke of the cutting tools at both ends of their movement by trapped fluid. The control of the fluid for driving, retracting, cushioning and generally operating the cut-

ting blades is a very delicate matter, and the successful operation of such a machine depends very largely upon the details and efficiency of the control mechanism.

Referring to the drawings, the machine to which this invention has been applied comprises a suitable base or frame, which rides by means of suitable rollers 1^a upon a track 1. This track is laid directly on the floor. A rack member 2 is rigid with the track and furnishes means for propelling the machine back and forth. The frame comprises supporting side members 3 which carry at their top a shaft 4, to which the battery of cutting mechanism is pivotally attached by means of a base plate 4^a. A segmental gear member 5 is rigidly attached to the bottom of the base plate 4^a carrying the battery of cutting cylinders to be later described. The curved portion of this segment has gear teeth 6, meshing with a small gear or pinion 7, which is driven by means of a shaft 8, an intermediate gear 9, shaft 10, sprocket 11, chain 12, sprockets 13 and 14, chain 15 and sprocket 16. The shaft 10 is driven through the positive connections just referred to from the motor shaft 17. A transmission and reversing gear mechanism, such as that used in automobiles, connects shaft 10 to a small gear lying directly behind the sprocket 11^a, which meshes with the large gear 9 and drives it in either direction, as will be understood. Therefore, by driving through the various connections above referred to, the fixed pinion 7 when rotated will drive segment 5, and so raise or lower the cutting tools as will be obvious. Shaft 10 carries a sprocket 11^a connected by a chain 11^b to a sprocket 20^a on shaft 20^b, which is connected through a train of gears including a reversing mechanism to pinion 20^c on shaft 20^d. The pinion 20^c meshes with rack 2, which is immovable. When the pinion 20^c is driven, the machine is caused to travel forward or back, upon the track members 1, and this mechanism is used to bring the machine into operative contact with the wall that is to be cut, and to withdraw the machine for repairs, removal, etc. My invention does not reside in the frame, supporting, or forward-driving part of the machine. A control lever 22 is connected to the driving segment gear mechanism by means of a connecting bar 26 and a lever arm 27 pivoted at 28, as illustrated. The

control lever 21 is connected by means of a bar 23 to a lever arm 24, pivoted on the shaft 25, as illustrated. By these levers the operator can readily control the relative distance of the machine from the surface being cut, and can shift the cutting contact of the machine up and down at will.

My invention has to do with the driving means of the cutting blades, and such means 10 will now be described.

It will be understood that a plurality of cutting mechanisms of which two only are shown,—are comprised in this machine. The particular number is not important, as 15 this is governed by the width of opening that the machine is built to cut, and may be varied according to the nature of the material that is to be encountered, the capacity of the machine desired, etc. It is only essential 20 that the cutting members be embodied in multiples of two, since according to my invention, they operate in pairs. Fig. 2 shows such a pair of cutting members, and any additional units would be simply duplicates of the pair illustrated.

Referring to Fig. 2, the cutting mechanism comprises a crank shaft 50 operating in a casing 51, and having attached thereto connecting rods 53 and 54, exactly as in the 30 case of an ordinary multiple cylinder explosive engine. It will be understood that the crank shaft 50 extends through other crank shaft casings 51 similar to that illustrated, and that it is driven at one or both ends by suitable mechanism for rotating it upon its longitudinal axis.

The connecting rods have suitable bearing members 55 engaging the crank shaft, and at their other ends are attached, by means 40 of connecting pins 56, to pistons 57 and 58, respectively, which are positioned in cylinders 59 and 60, respectively. These pistons have the ordinary piston rings forming a 45 fluid-tight contact with the interior walls of the cylinders just as in the ordinary explosive engine construction. The forward ends of the cylinders are closed by a bolted-on terminal plate member 61, having central openings 62 leading therethrough. Bolted 50 on to the exterior of the plate 61 are castings 63, to which are flexibly attached castings 64, the two castings together forming a passage 65, leading from the opening 62 to an opening 66 formed in the middle portion 55 of a plate 67 bolted on to the casting member 64, and forming an end wall of a cylinder 68, bolted thereto. The interior of cylinder 68 toward its forward end is reduced to a slightly smaller bore 68^a, and a 60 collar member 70 seats in the larger bore, against the shoulder formed between the two bores. This is forced into place with a tight fit, and is additionally held by pins 70^a. Toward its forward end, the bore 68^a 65 of the cylinder is further restricted by a

transition portion 71, beyond which the cylinder extends in a smaller bore, or neck portion 72. At its outer end, the cylinder is closed by a bearing member 73, clamped into the ends of the cylinder by screws 74. 70 Inside the large bore of the cylinder a piston member 80 is mounted, and makes close fit with the walls thereof by means of the ordinary piston rings. This piston member carries on its forward side an extension in the form of a hollow shaft 81 extending out through the bearing 73, and carrying on its external end one of the cutting tools of the machine.

This cutting tool comprises a body portion 90, having a rearwardly extending portion 91, which is bored out to receive the conical terminal head 92 of the shaft 81. This ferrule-like portion 91 is held on the end of the shaft 92 by means of a taper pin 93 extending therethrough, or by any other suitable means. Attached to the forward end of the body 90 are cutting chisels 94 formed with cutting edges 95. These latter are adapted to strike and chip off the surface of the wall being cut away. They are removable, being clamped in position by a plate member 96, cooperating with a lower integral portion 97 of the body 90 and bolts 98 extending between these two members and clamping them together, the cutting chisels being carried between.

A special wall and bearing member seats in the restricted second bore 68^a of the cylinder, between the collar 70 and the restricting portion 71, and furnishes an air-tight bearing and end wall for that portion of the cylinder beyond the piston 80. This member is built up of a series of removable discs 100, which are bolted together, making up what is substantially a solid block with annular internal recesses for receiving piston rings. A bolt 102 extends through the removable rings and holds them securely together. Between the discs 100 are piston rings 103. These are normally somewhat smaller than the shaft 81 and, therefore, bear resiliently against that member though held in position in the exterior bearing members. Such a construction furnishes an efficient lock against escape of pressure from the chamber 104 formed between this packing member just above described and the exterior head of the piston 80.

The piston 80, which is integral with the shaft 81, has an extension 80^a, which is in effect an enlargement of the shaft 81, extending into the chamber 104. This enlarged extension is circular, and carries a removable sleeve member 105, which is designed to fit into the circular opening formed by the collar member 70. On the other side of the piston 80 another extension is formed by means of a plug 106, fastened into the bore and forming an extension of

the shaft 81, and surrounded by a removable sleeve member 107. This is made to accurately fit into the opening 66 through the end plate 67. The space between the said end plate 67 and the rear side of the piston 80 forms a chamber 109.

It will be understood that the foregoing description applies to the cylinder 68, and its associated parts; and also that the companion cylinder 69 has exactly similar parts and members associated with it. The chambers 104 in the pair of cylinders are connected to each other by means of openings in their tops and a pipe 110 extending across from one cylinder to the other. This pipe 110 is connected by means of a pipe 111 to a supply main 112, which runs to a source of fluid pressure, such as a compressed air tank, or pump. In the pipe 111 is positioned a one-way automatic pressure-regulating valve 113, which is adapted to maintain a constant pressure in the pipe 110, and consequently in the connected chambers 104 of cylinders 68 and 69. It will be understood that the pressure in the supply tank is always greater than the pressure in the chambers 104, and that the valve 113 is so set as to simply admit additional pressure to make up for any fluid that escapes from the chambers 104, and does not permit any flow of pressure back into the main from the pipe 111.

Instead of a supply main 112 connected to each of the pipes 110 through a pressure-regulating valve 113 as illustrated in Fig. 2, I may use a single pressure-regulating valve 113^a in the line 112^a near where that main connects to the storage or compression tank T, thus maintaining a constant pressure of the desired amount in the main. In such case I provide in place of the valves 113 in pipes 111^a a wall 113^b through which the passage is in the form of a pin-hole opening 113^c. This is sufficient to permit additional fluid to flow in to replace the small amount that leaks out of the chambers 104, but is not large enough to permit any material amount of fluid to flow back out of those chambers, by reason of the pulsations caused by flow back and forth between the two chambers 104. The object is to keep each pair of chambers 104 so connected that their fluid content flows back and forth between them without material escape. Either construction described will secure this end. The modification just described is illustrated in Fig. 3.

There is on the market, and I may use it for 113^a, a valve which will vary the fluid pressure in main 112^a according to the inclination of the tool-driving cylinders. But such a valve is standard construction and not a part of my invention.

Another supply main 120 leads from a source of fluid pressure, such as the com-

pressed air tank T above referred to. This is separately connected through automatic pressure regulating one-way valves 114 to each of the chambers 115, in the cylinders 59 and 60. This connection is made by 70 means of ports 116, illustrated in Fig. 1. The ports do not lead directly to the chambers 115 but rather lead into the passages 65 between that chamber and the chamber 109.

The details of the pressure-regulating 75 valves 113, 113^a and 114, are not here illustrated, since they are standard constructions of which there are several suitable types on the market. The valve 114 is set so as to normally maintain a certain constant pressure in the chamber 115. It has an external adjusting member in the form of an arm 125, to which is attached a connecting bar 126, extending through suitable supports 127 and 128 to the forward end 80 of the cylinders. Beyond the support 128, the connecting bar has a terminal extension 129, slightly in advance of the forward end of the operating cylinder. Mounted on the forward end of the shaft 81, just behind the 90 cutting tool is an upward extension 130, which carries a rearwardly extending adjustable set screw 131. As the shaft 81 is reciprocated the set screw 131 moves in line with the terminal 129 of the rod 126. By 95 adjusting the screw 131 the terminal 129 and the screw may be made to come into contact at any desired point in the rearward limit of travel of the shaft 81. The end of rod 126 is threaded and an adjustable nut 133 is 100 carried thereon. This nut is positioned behind the guide support 128. A coil spring 134 attached to the other end of rod 126 normally urges the rod to the position where further travel is limited by adjustable nut 105 133. The pressure-regulating valve 114 may be slightly and momentarily opened by means of this mechanism, for the purposes hereinafter described.

The casing 51, cylinder 59, plate 61, and 110 casting 63, are all rigidly connected. The same is true of casting 64, plate 67, and cylinder 68. The two groups of members just referred to are connected by a flexible hose 140 fitted over the ends of castings 63 and 64 115 and clamped thereon to form a fluid tight joint by means of bands 141.

The operation of the device is as follows:

The machine having been brought into operative position in front of a ledge or 120 wall through which an opening is to be cut, power is supplied to drive the crank shaft 50. This causes the pistons 57, 58, to be reciprocated in the cylinders 59 and 60. Air in the chambers 115, passages 65 and chambers 125 109 is trapped, that is to say, there is no means of escape, and furthermore, it is kept under a constant pressure by means of supply through the main 120 and valves 114, as described. Consequently, when the pistons 130

are driven forward to the position illustrated by piston 57 the air in chambers 115 is driven through the passages 65 and into the chambers 109, and of course drives the movable pistons 80 forward. These, in turn carry the shafts 81, and consequently the cutting blades, forward with a quick stroke, which with the momentum of the shaft, etc., causes the blades to strike the surface of the 10 wall to be cut with sufficient impact to chip off pieces thereof. At the end of the forward stroke, which is illustrated at the top of Fig. 2 by the piston 57, the pistons are withdrawn, thereby exhausting air from 15 the chamber 109, and relieving the pressure on the rear of pistons 80, which are immediately withdrawn, or forced back, by reason of the pressure in chambers 104. By this means, the pistons 80, and the shafts 81 and 20 the cutting tools 90 carried thereby, are driven rapidly forward and back by compressed air. No positive driving of the cutting tool is employed, and this is highly important, since if such tools were forced 25 positively forward a certain distance, and were to strike substances which would not give away, something would have to break, as will be obvious.

The travel of the cutting tools forward 30 and back is positively cushioned at each end of the stroke by an air dash pot, as will be obvious from the construction. For example, looking at the cylinder 68 in section in Fig. 2, the cutting tool is shown in position 35 nearing the end of its rearward stroke. Further travel backward of the piston 80 will bring the extension 107 into the bore of passage 66. The sleeve member 107 is made to fit accurately into this bore, and consequently, further travel past the position illustrated will result in cutting off all escape of air from the chamber 109, and the trapped air will be compressed, furnishing a cushion 40 which will absolutely prevent the piston 80 from traveling as far as the end of the cylinder.

On the other hand, at the forward end of the stroke, the travel of the cutting tool is limited by an air cushion formed when the 50 forward extension 105 comes to the bore formed by the collar member 70, as illustrated in Fig. 1. Any further forward travel beyond the position shown in Fig. 1 causes the contact of collar 70 and piston member 105 to shut off escape of air from the space 150, which lies between the collar 70 and the forward side of the piston 80.

The members 105 and 107 are made of a 60 metal and in forms which will give a very accurate fit. They may be removed for repair or renewal when worn so that leakage of pressure would result. It will also be noted that as assembled the parts 106, 107, 80, 80^a, 81 and 105 are effectively one piece, being 65 rigidly connected.

The chambers 104 in each pair of operating cylinders are freely connected through the pipes 110. It will be observed from the arrangement of the crank shaft that the pistons 57 and 58 are reciprocated in opposite 70 directions. That is to say, one is always traveling forward when the other is traveling back, and vice versa. The same is true of pistons 80 in the two cylinders 68 and 69. Therefore, the air in chamber 104 of cylinder 75 68 is being compressed at a time when the pressure in the corresponding chamber 104 of cylinder 69 is being relieved. Therefore, there is a constant flow across and back between one chamber 104 to the other. This 80 pressure is kept up, and built up, when depleted, by supply from the main 112, as above referred to.

The maintenance of a proper pressure behind the pistons 80 is highly important. In 85 fact, the success of the machine largely depends upon this. If this pressure becomes reduced through leakage, or for any reason this pressure is not high enough, the piston 80 and the cutting tool will be withdrawn 90 too far, and too quickly, by means of the pressure in chambers 104, and likewise they will not be driven forward sufficiently far, or sufficiently quick to secure the desired cutting action. In order to avoid this condition, and to maintain the desired pressure between the pistons 57, 58, and 80, and particularly in order to immediately correct such a condition when it exists, the adjusting members 125, 126, and 131 above referred to 100 are provided. By means of these members, or equivalent construction, should the pressure between the two pistons fall below the required amount, with a consequent retraction of the cutting member beyond the point where it is intended to come, the set screw 131 will strike the terminal 129 of the adjusting rod 126. This, in turn, will move the arm 125 against resistance of spring 134 and will momentarily open the valve 114, 110 permitting a slight additional supply of fluid to the space between the two pistons. This feature is very important and highly efficient. It insures that an adjustment of air pressure will take place on the very 115 stroke that it becomes necessary, and prevents any undue strain upon the machine, or impairment of the cutting efficiency that would result from a depleted pressure between the two operating pistons.

When the battery of cutting cylinders is inclined downwardly, as for example when it is cutting from a wall near its base, that is to say, nearly down to the level of the track upon which the machine is mounted, the weight of the tool-carrying piston will naturally tend to cause those members to move forward more quickly, and to move farther, than would be the case where the machine is operating in a horizontal posi- 120 125 130

tion such as that illustrated in the drawings. And when the tools are working above the level position the reverse is true. In order to take care of these conditions, and to secure the proper cushioning and driving of the pistons in both directions and under varying angles of inclination, and to secure the proper quick rebound of the pistons on the return stroke, it may be desirable to provide means for increasing or decreasing the air pressure in chambers 104. This I can do by means of the pressure regulating valves 113, connecting to those valves an arrangement similar to that above described in connection with the valve 114. That is to say, means may be provided to momentarily open the pressure-regulating valve 113, said means being operated by forward travel of the tool-carrying pistons past a certain predetermined point. This is not illustrated in the drawings, since the construction is substantially the same, only reversed, as that already illustrated in connection with valve 114. Or I may use a pressure control valve 113^a of a standard construction that will automatically vary the pressure as the angle of inclination changes.

It will be observed that in the construction described herein all of the parts constituting the cylinder for driving the cutting tools are bolted together forming in effect an integral structure. It will also be observed that all of the bores incident to this tool-carrying cylinder are concentric, and in series so that the casting forming the operating cylinder may be machined out with one setting in a suitable boring apparatus. This is important since it is absolutely necessary that all of the bores be accurately aligned, and that they shall be permanently held in alignment.

It will also be understood that there is provided with this machine a loading mechanism, which however is not illustrated in the drawings. This mechanism is adapted to gather the material that is cut from the wall, as it falls to the floor beneath the cutting end of the machine, and to convey the broken material to the back of the machine, or to dump it into suitable cars for carrying it away. Such apparatus is not a part of this invention, and is therefore not illustrated or claimed. One successful way for doing this comprises an ordinary screw conveyor extending across the front of the machine at the floor line. This will gather the material and transfer it to a second conveyor running upward, rearward and to a point where it may be dumped into a car. This makes any manual handling of the material unnecessary.

It will be understood that modifications may be made in some of the parts illustrated and described, without departing from the principles of the invention disclosed. Many

additional advantages and functions of the apparatus will be apparent to those familiar with the art, from an understanding of the foregoing specification.

I claim:

1. In a machine of the class described a cylinder, a piston therein, a shaft extending forward from the piston and carrying a cutting tool, a rearward extension from said piston, an opening in the rear end wall of the cylinder adapted to receive the rearward extension and thereby to trap air behind the piston, and a removable sleeve member fitted on said rearward extension and adapted to make a close sliding fit in the said opening in the rear piston wall. 70

2. In a machine of the class described a tool-actuating mechanism comprising a cylinder, a piston slidable therein, a forwardly extending shaft attached to the piston and carrying cutting blades, a portion of the said shaft adjacent to the piston being enlarged, a removable sleeve member adapted to slip over and fit tightly on the said enlarged portion, and a collar member secured in the interior of the cylinder and adapted to receive the said sleeve member at the forward end of the stroke of the piston, whereby to trap air between the said collar member and the piston. 85

3. In a machine of the class described, comprising a cylinder and a tool-carrying piston adapted to reciprocate therein, the combination of extensions on each side of the said piston adapted to fit into openings leading from the respective ends of the chamber in which the piston travels, and removable sleeve members surrounding said projections and accurately fitted to slide into and close the bores forming the said openings from the chamber in which the piston travels. 95

4. In a machine of the class described, a cylinder, a piston therein, a shaft extending forward from the piston and carrying a cutting tool, a rearward extension from said piston, and an opening in the rear end wall of the cylinder adapted to receive the rearward extension at the end of the return stroke and thereby to trap air between the piston and rear wall to cushion rearward movement of the piston. 105

5. In a machine of the class described, a tool-actuating mechanism comprising a cylinder, a piston slidable therein, a forwardly extending shaft attached to the piston and carrying cutting blades, a portion of the said shaft adjacent to the piston being enlarged, and a detachable collar member secured to the interior wall of the cylinder and adapted to receive the said enlarged portion of the shaft at the forward end of the stroke of the piston, whereby to trap air between the said collar member and the piston. 120

6. In a machine of the class described, the

combination of a cylinder and a tool-carrying piston adapted to be reciprocated therein, the piston having extensions on each side adapted to fit alternately into openings leading from the respective ends of the chamber in which the piston travels, whereby to trap air and cushion the movement of the piston at each end of the stroke.

7. In a machine of the class described, 10 cylinders arranged in cooperating pairs, each of said cylinders enclosing a tool-carrying piston, means to drive the pistons simultaneously in opposite directions the chambers formed in said cylinders in advance of 15 the said pistons being connected by a passage leading between the two cylinders, whereby air is driven back and forth between said cylinders.

8. In a machine of the class described, 20 cylinders arranged in cooperating pairs, each of said cylinders enclosing a tool-carrying piston, the tool being connected thereto by a forwardly extending shaft, said shaft being surrounded by a fluid-tight bearing member at the forward end of the cylinder, a pipe connecting the chambers in the two cylinders formed between the forward side of their pistons and the said bearing members at the forward ends of the cylinders, 30 whereby fluid pressure may pass from one of the said chambers to the other as the pair of pistons are reciprocated in opposite directions.

9. In a machine of the class described, 35 tool-driving cylinders arranged in cooperating pairs, each of said cylinders comprising a piston, the tool being connected thereto by an integral forwardly extending shaft, said shaft being surrounded by a fluid-tight bearing member at the forward end of the cylinder, an open pipe connecting the chambers in the two cylinders formed between the forward sides of their pistons and the said bearing members at the forward ends of the cylinders, 45 whereby fluid pressure may pass from one of the said chambers to the other as the pistons are reciprocated in opposite directions, and means to feed air into the said pipe from a source of constantly maintained fluid pressure.

10. In a machine of the class described, tool-actuating cylinders arranged in cooperating pairs, each of said cylinders comprising a tool-carrying piston, the tool being connected thereto by an integral forwardly extending shaft, said shaft being surrounded by a fluid-tight bearing member at the forward end of the cylinder, a pipe connecting the chambers in the two cylinders formed 55 between the forward side of their pistons and the said bearing members at the forward ends of the cylinders whereby fluid pressure may pass from one of the said chambers to the other as the pistons are reciprocated in opposite directions, and a connection lead-

ing to the said pipe from a source of fluid pressure, said connection comprising an automatic one-way pressure regulating valve, whereby to maintain a fluid pressure in the two chambers referred to.

11. In a machine of the class described, the combination of a primary compression cylinder and a secondary tool-driving cylinder, a pipe leading into the said primary compression cylinder, said pipe being connected to a source of fluid pressure, a valve in said pipe adapted to maintain a predetermined minimum pressure in the said compression cylinder, and means adapted to be moved by the tool driven by the secondary cylinder whereby to open the valve to admit additional pressure to the compression chamber when the tool moves backward past a predetermined point.

12. In a machine of the class described, the combination of a plurality of primary compression cylinders and a plurality of secondary tool-driving cylinders, pipes leading into each of the said primary compression cylinders, said pipes being connected to a source of fluid pressure, a valve in each of said pipes adapted to maintain a predetermined minimum pressure in each of the said compression cylinders, and means actuated by travel of the tools to open the valves to admit additional pressure to the compression chambers when the tool moves backward past a predetermined point.

13. In a mechanism of the class described, the combination of a primary compression cylinder and a secondary tool-actuating cylinder, the tool being carried upon a shaft extending from a piston reciprocating in the tool-actuating cylinder, a pipe leading into the compression cylinder, said pipe being connected to a source of fluid pressure through an automatic pressure-regulating valve adapted to maintain a minimum pressure in the compression chamber, and means actuated by movement of the tool-carrying piston to open said valve to admit additional pressure to the compression cylinder when the said tool carrying piston moves backward past a certain predetermined point.

14. In a machine of the class described, the combination of a primary driven piston, a secondary piston driven by fluid pressure controlled by the first piston, pressure chambers before and behind the secondary piston, a source of fluid pressure connected to each of said chambers, and means actuated by travel of the secondary piston to regulate the fluid pressure in said chambers.

15. In a machine of the class described, the combination of a primary driven piston, a secondary piston driven by fluid pressure controlled by the first piston, pressure chambers before and behind the secondary piston, a source of fluid pressure connected to each of said chambers, and automatic means

for controlling the flow of pressure from the said source to the said chambers, whereby to maintain the fluid pressure in the chambers.

16. In a machine of the class described, 5 a primary compression cylinder having a piston adapted to reciprocate therein, a connection from the said compression cylinder to the secondary cylinder, a piston adapted to reciprocate in the secondary cylinder by 10 reason of air pulsations generated thereinto by the piston of the primary cylinder, a forwardly extending shaft fixed on the piston in the secondary cylinder, a cutting tool on the exterior end thereof, an air passage leading 15 from a source of fluid pressure to the primary compression cylinder, an automatic pressure regulating valve controlling said passage and adapted to maintain a minimum pressure therein, a connecting rod extending

from the said valve to the forward end of 20 the tool actuating cylinder, a support for the forward end of the said rod, adjustable means to limit the forward travel of the rod, a spring normally urging the rod forward to its stop position, an extension on the tool- 25 carrying shaft adapted to contact with the forward end of the rod upon the withdrawal of the tool-carrying shaft, an adjustable contact member between said extension and the end of the rod whereby to adjust the 30 point of contact thereof, the rear end of said rod being adapted to open the said pressure regulating valve when the rod is forced back.

In testimony whereof, I have hereunto set 35 my hand.

BURT A. CHUBBUCK.
